United States Patent Office

Des. 219,179
Patented Nov. 10, 1970

219,179

EXPOSURE METER

John T. Armbruster, Niagara Falls, N.Y., assignor to
American Optical Corporation, Southbridge, Mass., a
corporation of Delaware

Filed Nov. 4, 1969, Ser. No. 19,941

Term of patent 7 years

Int. Cl. D16—07

U.S. Cl. D61—1

FIG. 1.

FIG. 2.

FIG. 3.

FIG. 4.

FIG. 1 is a front perspective view of an exposure meter showing my new design;

FIG. 2 is a top plan view of the exposure meter shown in FIG. 1;

FIG. 3 is a side elevational view of the exposure meter, the opposite side thereof, not shown, being of substantially the same appearance; and

FIG. 4 is a rear elevational view of the exposure meter shown in FIGS. 1, 2 and 3.

I claim:

The ornamental design for an exposure meter, substantially as shown and described.
